CLAIM

The ornamental design for a packaging plug, as shown and described.

DESCRIPTION

FIG. 1 is a perspective view of a packaging plug showing the ornamental design.

FIG. 2 is a side view of a packaging plug showing the ornamental design.

FIG. 3 is a side view of a packaging plug showing the ornamental design.

FIG. 4 is a top-down view of a packaging plug showing the ornamental design; and,

FIG. 5 is a bottom-up view of a packaging plug showing the ornamental design.

The broken lines shown illustrate portions of the packaging plug and form no part of the claimed design.

1 Claim, 5 Drawing Sheets
